UNITED STATES PATENT OFFICE.

CHARLES J. DIEGES, OF NEW YORK, N. Y., ASSIGNOR TO DIEGES & CLUST, OF NEW YORK, N. Y., A CORPORATION OF NEW YORK.

DESIGN FOR A RING.

Application filed March 26, 1924. Serial No. 9,070. Term of patent 3½ years.

To all whom it may concern:

Be it known that I, CHARLES J. DIEGES, a citizen of the United States, residing in the borough of Manhattan, city, county, and State of New York, have invented a new, original, and ornamental Design for a Ring, of which the following is a specification, reference being had to the accompanying drawing, forming a part thereof.

Fig. 1, is an enlarged top plan view of a ring, showing my new design;

Fig. 2, is an edge elevation of the same. What I claim is, The ornamental design for a ring, as shown.

CHAS. J. DIEGES.
